UNITED STATES PATENT OFFICE.

DOMENICO CALARCO, OF BURLINGTON, VERMONT.

DESIGN FOR A WALL AND MANTEL ORNAMENT OR THE LIKE.

Application filed July 7, 1927. Serial No. 22,682. Term of patent 3½ years.

To all whom it may concern:

Be it known that I, DOMENICO CALARCO, a citizen of the United States, residing at Burlington, in the county of Chittenden and State of Vermont, have invented a new, original, and ornamental Design for Wall and Mantel Ornaments or the like, of which the following is a specification, reference being had to the accompanying drawing, forming part thereof.

I claim:

The ornamental design for a wall and mantel ornament or the like as shown.

DOMENICO CALARCO.
